No. 37,481.

Patented July 11, 1905.

UNITED STATES PATENT OFFICE.

ESTON S. CHENEY, OF OAKLAND, CALIFORNIA.

DESIGN FOR A MOUNT.

SPECIFICATION forming part of Design No. 37,481, dated July 11, 1905.

Application filed March 25, 1905. Serial No. 252,081. Term of patent 3½ years.

To all whom it may concern:

Be it known that I, ESTON S. CHENEY, a citizen of the United States, residing in Oakland, county of Alameda, State of California, have invented a new, original, and ornamental Design for Card-Mounts, reference being had to the accompanying drawing, in which the drawing shows a plan view of a mount showing my design.

I claim—
The ornamental design for a card-mount as shown.

ESTON S. CHENEY.
